UNITED STATES PATENT OFFICE.

JOHN PUTNAM, OF PHILADELPHIA, PENNSYLVANIA.

BIRD-CAGE.

SPECIFICATION forming part of Letters Patent No. 311,848, dated February 3, 1885.

Application filed January 5, 1884. (No model.)

To all whom it may concern:

Be it known that I, JOHN PUTNAM, of Philadelphia, in the county of Philadelphia and State of Pennsylvania, have invented a new and Improved Bird-Cage, of which the following is a full, clear, and exact description.

The object of my invention is to provide a certain new and useful improvement in bird-cages, whereby the cleaning of the cage is facilitated and the appearance of the cage is improved.

The invention consists in the peculiar construction and arrangement of parts, as hereafter fully described, and pointed out in the claims.

Reference is to be had to the accompanying drawings, forming a part of this specification, in which similar letters of reference indicate corresponding parts in all the figures.

20 Figure 1 is a plan view of the bottom plate of my improved bird-cage. Fig. 2 is a longitudinal sectional elevation of the same on the line *x x*, Fig. 1. Fig. 3 is a cross-sectional elevation of the same on the line *y y*, Fig. 1.

25 The bottom plate, A, of the bird cage is made of glass, and is provided with an upwardly-inclined rim, B, which projects beyond the base of the bird-cage frame. The plate A is provided at two opposite sides with 30 slots C, through which locking-pins D, provided with heads D' D'', are passed. The pins D are held to slide in apertures of the base flange or rim E of the bird-cage frame I, and are held raised by springs a, secured to said 35 flange or rim E and engaging the heads D' of the pins. The bird-cage frame I is secured to the bottom plate, A, by placing it on the said bottom plate, depressing the pins against the action of the springs to force 40 them through the slots of the said bottom plate, and then giving them a quarter-turn, the springs, upon the release of pressure on the pins, forcing the same upward and firmly locking the cage-frame to the bottom 45 plate. To remove the cage-frame from the bottom plate, it is only necessary to depress the pins and give them a quarter-turn to cause their lower heads, D'', to register with the slots

50 C of the bottom plate, when the cage-frame can be taken off. Cups F for feed or water are formed on the rim of the bottom plate, or 55 the said cups can be formed as wickets for receiving cups G for feed or water. A tubular projection, H, may be formed in the middle of the bottom plate, which tubular projection is to receive a button or head formed on the lower end of a rod or wire, by which the bottom plate is suspended from the bird-cage frame, or the said tubular projection can receive the lower end of a rod, to which perches, 60 &c., are fastened.

I do not limit myself to the means herein shown and described for fastening the cage to the bottom plate, but may use any other suitable means.

65 The above-described bottom plate is very simple in construction, and can be readily cleaned, as the sand or gravel placed on the same does not adhere to it, and it cannot be defaced by oxidation or by the sand, water, 70 &c., as the usual metal bottom of cages are. The glass bottom also gives the cage a better appearance.

Having thus described my invention, I claim as new and desire to secure by Letters Patent— 75

1. The bird-cage bottom plate, A, made of glass, and provided with the feed-cups F and openings C, the said feed-cup being integral with the bottom plate, substantially as herein shown and described.

80 2. The combination, with a bird-cage frame, I, having bottom rim, E, and the bottom plate, A, having slots C, of the spring-pressed pins D, fitting loosely in apertures of the said bottom rim, and provided with the heads D' D'', substantially as herein shown and described.

85 3. The bird-cage bottom plate, A, made of glass, and provided with the openings C, the feed-cups F, and the central tubular projection, H, substantially as herein shown and 90 described.

JOHN PUTNAM.
